AUTOMATIC OPENING AND CLOSING CONTAINER

John A. Yerkes, New York, N. Y.

Application November 13, 1946, Serial No. 709,443

8 Claims. (Cl. 206—1.5)

1

This invention relates to containers and particularly those of the type adapted to hold cigarettes or similar articles. It is desirable to keep some articles, such as cigarettes, in a container with a lid thereon and to be able to open said lid automatically.

One of the objects of the invention is to provide a container wherein the lid is closed when held in one position and is automatically opened as the container is turned or inverted, the opening and closing action being arranged so that articles will not be expelled unintentionally from the container during the turning operation.

Another object of the invention is to provide a container which will automatically open and close in a foolproof manner when the container is full and also when only partly full.

Still another object of the invention is to provide a mechanism which is sturdy, light in weight, and inexpensive to manufacture. In previous devices, complicated arrangements of springs and weights have been employed which are not required in the present invention.

Other objects, features, and advantages will become apparent from the following description and drawings which are merely exemplary.

In the drawings:

Fig. 1 is a longitudinal vertical sectional view of the device when it is in an upright or open position.

Fig. 2 is a view looking upwardly when the container is in the upright position as seen in Fig. 1.

Fig. 3 is a section taken along the line 3—3 of Fig. 1, the figure being broken along the center-line.

Fig. 4 is a longitudinal vertical sectional view when the container is in an inverted or closed position.

Fig. 5 is a view looking upwardly when the container is in inverted closed position seen in Fig. 4.

Fig. 6 is a section taken along the line 6—6 of Fig. 4, the figure being broken along the center line.

Fig. 7 is a vertical cross-sectional view taken along the line 7—7 of Fig. 4.

Fig. 8 is a detailed sectional view of the weight.

Fig. 9 is an isometric view of one of the cover lids.

Fig. 10 is an isometric view of the shield located between the two lids.

Fig. 11 is a side view showing the device as it is being turned on its end.

Fig. 12 is an end view showing the device as it is being turned sideways.

2

In a preferred form of the invention, receptacle 1 may be made of a plastic material, wood, metal, or the like, and has a bottom portion which is preferably cut away to form a pair of apertures 3, 3 (Figs. 1, 2) and shoulders 4 for the reception of plastic or glass windows 2 so that the contents such as, for example, cigarettes 49 can be seen clearly when the container is viewed from the bottom (Figs. 1, 2).

It is evident that the bottom portion may be solid or may have various types of designs thereon as desired. The longitudinally extending walls 41 of the receptacle preferably are made straight with rounded ends 42, but, of course, various shaped receptacles may be employed, and, as an example, the receptacle may be rectangularly shaped. The straight walls 41 can be vertically grooved on the inside to form shoulders 5 and recesses 43 interiorly of the longitudinal walls 41, said recesses being adapted to receive a weight housing 11, the purpose of said housing 11 being described hereafter.

Shield 8, resting on ledge 6, may be secured to receptacle 1 by any suitable means such as by screws 10 engaging screw threaded holes 10' (Figs. 1, 7, 10). Depending apron 9 of shield 8 extends downwardly to rest against weight housing 11 serving to hold said housing 11 against accidental displacement. The shield 8 also serves to conceal the mechanism.

Weight housing 11 has four recesses 12 (Fig. 3) to provide space for the operation of the two pairs of hinges 16 (Figs. 1, 9) having depending arms 14, said weight housing being nested within the receptacle between shoulders 5. Four pivot screws 13 in housing 11 pass through apertures 15 in depending arms 14 so as to pivotally mount the hinges on the weight housing. The depending arms 14 are joined by bridge 17 of the hinge there being a central projecting portion 18 terminating in an arcuate portion 20 and chain hole 19 may be located adjacent the junction of portions 18 and 20 of the hinge. The hinges in turn may be secured to the pair of lids 23 in any suitable manner such as by screws 22 (Figs. 6, 9) extending through holes in said hinges. It is evident that if plastic material is used for the lids that the hinges may be molded inserts in said lids or that the lids and hinges may be integrally formed of any desired material.

The lids are shaped so as to conform generally to the shape of the receptacle with the operating or working ends 25 substantially increased in thickness to assist in the opening action thereof.

The corners 24 of said operating ends are bevel-

elled or shaped so as to provide clearance when the lids swing downwardly within the sloping walls 26 of the weight housing 11 to the position shown in Fig. 1. The weight housing 11 preferably is rectangular in exterior shape so as to fit into the receptacle. The bottom of the weight housing may be hollowed out to reduce weight such as shown at 28 (Fig. 1).

The interior of the housing is provided with sloping walls 26 which preferably are conical, but may be pyramidal, hemispherical, or a shape having the function of the conical walls as discussed hereafter. So as to reduce length, the conical shaped walls are frusto-conical as shown with an opening 27 near the apex of the cone for economy of width and so as to enable the use of a heavier weight. Cylindrical portion 29 is provided in the bore of the weight housing 11, the cylindrical portion, although not essential, serving to lessen the likelihood of vibration and undesirable shifting of the weight when the receptacle is turned in operation thereof.

A pair of cover plates 30 (Figs. 1, 4, 6) may be secured to the top of weight housing 11 by screws 32 extending through holes in said cover plates in a conventional manner.

Chain 33 may be made from a length of chain intersecting and joined to a second length of chain at a point intermediate the ends of said second chain so that the chain assembly can take a shape similar to that of an inverted T when the receptacle is in the position shown in Fig. 4. One end of the chain is fastened to the weight and each of the ends fastened to one of the lids 23. The branch ends may be threaded through each of the chain holes 19 (Fig. 9) in the hinges 18 and then a small pin 35 inserted for the purpose of holding the chain therein. It is evident that the pin and chain also may be soldered to the hinge or otherwise suitably fastened thereto. The long branch of the chain is passed through the bore of weight 36 through a small washer 34 and can have a pin 35 inserted through the terminal link and preferably secured by soldering. It is evident that various equivalent methods or means of securing the chain to the lids and to the weight may be employed.

Weight 36 preferably is conical in form but may be given other suitable shapes which are capable of performing the desired operation of the weight.

The best operation of the device is obtained when the weight conforms substantially in exterior shape to the shape of the bore of housing 11. In the embodiment shown, the weight is frusto-conical in exterior form with a joining cylindrical portion 39, the cylinder being substantially the same length as the cylindrical portion 29 of the bore of weight housing 11. The bore 38 of the weight may be enlarged to allow lateral movement of the chain (Fig. 4), the bore preferably flaring out to a conical shape 37. In order to give the desirable weight, a portion 38 of the bore is cylindrical and relatively small in diameter as will be explained hereafter.

The chain must be of the correct length to allow the requisite lateral movement of the weight in the weight housing 11. The chain could be eliminated by using an alternate construction wherein the lids 23 would have relatively heavy weights at the working ends 25 so that the lids would be counterbalanced and tend to swing themselves to open position when the container is brought to the upright position of Fig. 1. A linkage also could be used in place of the chain to cause opening of the lid by the

weight. It also is to be understood that a single lid container may be used instead of a double lid.

Describing the operation, when the container is placed on a table or held upright (Fig. 1), weight 36 will rest on the bottom of the bore of weight housing 11, lids 23 having been swung to open position by the action of the weight moving downwardly. The action of the weight is transmitted to the lids by means of chain 33 which swings the lids on their hinges 18 to the position shown in Fig. 1. It is preferable that the length of the weight and the conical surface thereof be so related to the conical bore of the weight housing that there will not be a tight fit therebetween so that there will be no danger of sticking. This, of course, could also be taken care of by proper lubrication of the surfaces.

When the container is in the inverted or closed position (Fig. 4), weight 36 will rest on the working ends 25 of lids 23 thus holding the lids in a closed position against the action of the weight of the cigarettes tending to open said lids. The top of the container will have the appearance as indicated in Fig. 1. It is important to prevent spilling the contents of the container as the receptacle is changed from the upright to the inverted position and therefore the lids must close before the container has been rotated to the point where gravity will act upon the contents and cause them to spill out. This means that the weight actuating the closing of the lids must operate before gravity acts upon the contents to cause them to fall out of the container. The angle of the walls of the bore and its relation to the normal horizontal and vertical axis of the container is made such that regardless of the direction in which the container is rotated in the action of inversion, the weight 36 will move under the action of gravity along the sloping walls 26 to urge lids 23 to a closed position. This takes place, in the embodiment shown, before the container has been rotated 75°. For this reason, there is no delicate balancing between the weight of a counterbalance and a spring and there are no intricate slides or other friction-causing elements necessary, such elements being difficult to assemble, adjust, and maintain in operating condition. The conical weight shown bears on the conical bore of the housing so that there is but a single line of contact.

Referring to Fig. 11, as the box is tilted end for end from an upright to an inverted position, the angle of the wall 44 relative to the normal vertical axis 47, is made such that the weight 36 will start its movement to the left so as to close lids 23 before the cigarettes 49 can slide out of the box. The angle of the wall 44 relative to the vertical axis of the box must be such that the angle of repose of the weight, as it rests on wall 44, is reached and the weight starts its movement before the contents of the receptacle can move. The angle of repose, as is well known, is the angle which the plane of contact between two bodies makes with the horizontal when the upper body is just on the point of sliding. It also is sometimes defined as the angle whose tangent is the coefficient of friction between the bodies. It is thus seen that when the angle of repose is reached as the receptacle is turned, a very slight further movement or a disturbing of the equilibrium of the weight will cause movement thereof to the left. Similarly, in Fig. 12, if the box is turned from an upright to an inverted position around the axis which is longitudinal of the receptacle, weight 36 will slide on wall 45 (Fig. 12)

to close the lids 23 thereof before the cigarettes in the box can slide or roll out and be expelled.

It is thus seen that the angle of repose of the weight is reached and passed before the angle of repose of the contents becomes affected by the turning. This is achieved by sloping the walls of the housing containing the weight and by proportioning and arranging the parts in such a manner so as to obtain the best possible operation of the device.

The weight, when in the position shown in Fig. 1, can be arranged so that there is a pad of felt (not shown) between the end of the weight and the bottom wall 46 of the receptacle so as to assist in preventing sticking of the weight to the surface 26 after prolonged inactivity. The felt also will tend to reduce the noise which might occur when the weight reaches the bottom of the weight housing.

It is to be understood that the details of construction may be varied, and that the receptacle can be used for many purposes and substances without departing from the scope of the invention as defined in the appended claims.

I claim:

1. In a receptacle, an article storing compartment, pivot means on said receptacle, a lid mounted on said pivot means, said lid having a compartment covering portion on one side of the pivot means and an extension on the opposite side of the pivot means, a weight, a weight housing having upwardly diverging walls when in upright position, said extension overlying said housing, and means opening said lid when the receptacle is in upright position, said weight sliding down said diverging walls as the receptacle is rotated toward an inverted position, said weight engaging said lid on the side of the pivot means opposite to said opening to close the same.

2. In a receptacle, an article storing compartment, pivot means on said receptacle, a lid mounted on said pivot means, said lid having a compartment covering portion on one side of the pivot means and an extension on the opposite side of the pivot means, a weight, a weight housing having upwardly diverging walls when the receptacle is in an upright position, said extension overlying said housing, and connecting means between the weight and said lid extension, said connecting means being of a length such that the weight pulls on said lid extension to open said lid when the receptacle is in upright position and the weight has moved toward the bottom of said weight housing, said weight sliding down the diverging walls by gravity as the receptacle is rotated manually toward an inverted position, said weight engaging and pressing on the lid extension causing said lid to close said compartment when the receptacle is in inverted position.

3. In a receptacle, an article storing compartment, a hinged lid pivot means on said receptacle, a lid mounted on said pivot means, said lid having a compartment covering portion on one side of the pivot means and an extension on the opposite side of the pivot means, a weight, a weight housing having upwardly diverging walls when said receptacle is in upright position, said extension overlying a portion of said weight housing, and flexible means connecting said extension with the weight and holding the lid in open position when the receptacle is in upright position, said weight sliding down said diverging walls as the receptacle is inverted to-

ward an inverted position, said weight engaging said lid extension, so as to close the same.

4. In a receptacle, an article storing compartment, pivot means on said receptacle, a lid mounted on said pivot means, said lid having a compartment covering portion on one side of the pivot means and an extension on the opposite side of said pivot means, a conical shaped weight engageable with said lid to close the same, a conical shaped weight housing having a bore with upwardly diverging walls when in upright position, said bore being of greater length than the weight, said extension overlying said housing, and means opening said lid when the receptacle is in an upright position, said weight sliding down said diverging walls by gravity as the receptacle is rotated in any direction toward an inverted position and engaging said lid extension and closing the same.

5. In a receptacle, an article storing compartment, pivot means on said receptacle, a lid mounted on said pivot means, said lid having a compartment covering portion on one side of the pivot means and an extension on the opposite side of said pivot means, a conical weight engageable with said lid to close the same, a weight housing having a bore with conical upwardly diverging walls when in upright position, said extension overlying said housing, and flexible means connected to said weight and holding said lid in open position when the receptacle is in an upright position, said weight sliding down said diverging walls by gravity as the receptacle is rotated in any direction toward an inverted position and engaging said extension of the lid and closing the same.

6. In a receptacle, a pair of article storing compartments, a pair of pivots on said receptacle, a pair of lids each mounted on one of said pivots, each of said lids having compartment covering portions on one side of its pivot and having an operating extension on the other side, a weight, a weight housing having upwardly diverging walls when the receptacle is in upright position, said lid extensions overlying said housing, and means opening said lids when the receptacle is in upright position, said weight being slidable by gravity along said diverging walls as the receptacle is inverted in any direction until the weight contacts said extensions and closes said lids.

7. In a receptacle, a pair of article storing compartments, a pair of pivots on said receptacle, a pair of lids each mounted on one of said pivots, each of said lids having compartment covering portions on one side of its pivot and having operating extensions on the other side, a weight, a weight housing having upwardly diverging walls when the receptacle is in upright position, said lid extensions overlying said housing, and flexible connecting means between said weight and said extensions opening said lids when the receptacle is in upright position, said weight being slidable by gravity along said diverging walls as the receptacle is inverted in any direction until the weight contacts said extensions and closes said lids.

8. In a receptacle, an article storing compartment, a pivot means on said receptacle, a lid mounted on said pivot means, said lid having a compartment covering portion on one side of the pivot and an extension on the opposite side of the pivot, a weight, a weight housing having upwardly diverging walls when the receptacle is in upright position, said walls defining a bore facing said extension, the angle of slope of said walls being of

such magnitude that when the receptacle is manually rotated in any direction, said weight will move along said wall by gravity to engage said lid extension and close the same as the receptacle is rotated toward a horizontal position so that articles will not spill from said compartment, and means connected to said lid extension holding said lid in open position when the receptacle is upright and the weight is away from said lid extension.
